UNITED STATES PATENT OFFICE

NETTIE M. ELBON, OF CHARLESTON, WEST VIRGINIA

TROUGH-SUPPORTING RACK

Application filed January 26, 1928. Serial No. 249,615.

This invention is a collapsible rack for supporting a trough designed to be used in connection with juvenile tooth-brush drills and the like.

It is now common practice in the public schools to strongly emphasize the importance of dental hygiene, and tooth-brush drills have become a part of the daily school routine in many localities. However, the effectiveness of such drills is often impaired and proper instruction hampered, to say nothing of insanitary conditions being created, by the lack of proper and convenient facilities for catching and disposing of the saliva, water, etc. expelled from the mouths of the children during such drills. The effective disposal of this refuse is necessary and important not only for sanitary reasons, but also to prevent untidy conditions in the school room, or other quarters where the instruction is being given.

One of the objects of the invention is to provide a portable supporting rack of the character described, which may be placed in any desired position in a school room, so that the children may be conveniently assembled about it for the desired tooth-brush drills. A further object is to provide a stand of the character mentioned, constructed so that it may be collapsed or folded into compact form, for convenient storage when not required.

The invention will be hereinafter fully set forth and particularly pointed out in the claims.

In the accompanying drawings:—

Figure 1 is a side elevation illustrating a rack constructed in accordance with the invention. Figure 2 is a top plan view of the rack with the trough removed. Figure 3 is an end view of one of the uprights. Figure 4 is a top view of one form of trough. Figure 5 is a similar view of a modified form of trough.

Referring to the drawing, *a*, *a*, represent two uprights, and *b*, *b*, and *c*, *c*, stay rods or braces by means of which the uprights are maintained in spaced relation, so that they will stand in upright positions. These parts may be constructed of any desired ma-

terial, but as shown in the drawing they are constructed of rod-like metal bent to the desired shape.

Referring particularly to Figure 2, it will be noted that each upright *a* is provided with legs 10, connected by a transverse bottom member 11, and side members 12. Said side members at their upper ends are bent downwardly as indicated at 13, and horizontally as indicated at 14 to provide a trough support.

The brace rods are arranged in four sets of two rods each. For instance, each rod *b* is provided at one end with a hook portion 15, shaped to removably engage a complementary portion 16 of an upright *a*, the other end of each of said rods *b* being provided with an eye 17. In a similar manner each rod *c* is provided with a hook portion 18, shaped to engage a complementary portion 19 of an upright *a*, the other end of each of said rods *c* being provided with an eye 20. As clearly shown in the drawings. The two rods *b*, *b*, of each upright *a* converge laterally inward and are also inclined downwardly, so that the eyes 17 of both of said rods are brought into register with each other. In a similar way the rods *c* also converge laterally inward and are inclined upwardly, so that the eyes 20 not only register with each other, but also with the eyes 17. A rod or bolt 21 is removably inserted through the registering eyes 17 and 20, so that the rods *b* and *c* are held against relative movement and the uprights *a* are firmly and rigidly held in vertical position.

It will thus be seen that the rods *b* and *c* are so arranged that two rods *b* and two rods *c* are each connected at one end to a frame *a* at relatively spaced points both vertically and laterally, and the other ends of said rods are brought together. The converged ends of both sets of rods are then detachably connected with each other.

The trough may be of any desired form, two examples being shown in the drawing. The form illustrated in Figure 4 consists of two sections 25, 25 having bevelled side walls and a flange 26. The contiguous portions of the flanges of adjacent sections are

hinged together as indicated at 27, so that when the two sections are opened to the position illustrated in Figure 1, the adjacent portions of the flanges will abut and folding of the trough is prevented in suitable manner. Each trough is provided with a drain opening 28 which may be closed by a suitable plug.

In the form illustrated in Figure 5, the trough is shown as consisting of a single section 30. It is to be understood that the troughs may be made of any desired material, but it is preferred to make them of sheet metal and to coat them with a baked enamel, or other form of impervious coating which will provide a hard, polished surface, capable of being easily cleansed and maintained in a sanitary condition.

The advantages of the invention will be readily apparent to those skilled in the art to which it belongs. For instance, it will be particularly noted that a very small and inexpensive stand or rack is provided, for rigidly supporting a trough in a position to permit the convenient assembly of children around it for toothbrush drills. It will also be observed that the device is exceedingly simple and inexpensive in construction, and by reason of the collapsible feature it may be readily knocked down and conveniently stored when not required, and yet may be quickly assembled and placed in position on the floor of the school room whenever required.

It is to be understood, that although the invention has been specifically described as applicable for use in the conducting of toothbrush drills, it is not limited to such use, but obviously may be employed in various other ways and for many different purposes, without departing from the spirit of the invention.

Having thus explained the nature of the invention and described an operative manner of constructing and using the same, although without attempting to set forth all of the forms in which it may be made, or all of the forms of its use, what is claimed is:

1. A rack of the character described comprising two uprights each provided with 50 brace rods removably connected therewith and also with trough supporting portions, and means removably connecting the brace rods of the respective frames with each other so as to maintain said frames in normally fixed spaced relation.

2. A rack of the character described comprising two uprights each provided with brace rods connected at one end therewith, the free ends of said brace rods having eyes 60 positioned to register with each other, and a pin removably engaging said eyes while in register so as to maintain said uprights in normally fixed spaced relation, said uprights being provided with trough supporting portions.

3. A rack of the character described comprising two uprights each provided with a plurality of upper and lower stay rods, the stay rods of the respective uprights converging toward each other and meeting at one end, and means for detachably connecting the meeting end portions of the respective stay rods so as to maintain said uprights in normally fixed spaced relation, said uprights having trough supporting portions. 70

4. A rack of the character described comprising two uprights each having trough engaging portions and each provided with upper and lower pairs of stay rods extending therefrom, each pair of stay rods converging laterally so as to meet at their free ends, and the upper and lower sets of stay rods of each upright also converging laterally so as to meet at their free ends, and means removably connecting the meeting ends of all of the stay rods of the respective uprights so as to maintain said uprights in normally fixed spaced relation. 80

5. A rack of the character described comprising two uprights each having trough engaging portions, stay rods each having hooks at one end removably engaging an upright, the other ends of the respective stay rods being provided with eyes, and a pin removably engaging said eyes so as to maintain said uprights in normally fixed spaced relation. 90

6. A rack of the character described comprising two uprights each formed of rod-like material bent to form legs and a body portion, the upper part of the body portion being depressed to provide a trough support, stay rods each having one end removably engaging an upright, and means detachably connecting the other ends of the stay rods of the respective uprights with each other so as to maintain said uprights in normally fixed spaced relation. 100

In testimony whereof I have hereunto set my hand.
